Inventor

UNITED STATES PATENT OFFICE.

PHILLIPS ABBOTT, OF YARMOUTH, MAINE.

FIREPLACE CHUTE OR ASH DROP.

Application filed July 12, 1924. Serial No. 725,616.

all whom it may concern:

Be it known that I, PHILLIPS ABBOTT, a resident in Yarmouth, in the county of Cumberland and State of Maine, a citizen 5 of the United States, have invented a new and useful Improvement in so-called Fireplace Chutes or Ash Drops, of which the following is a description, reference being had to the accompanying drawings, forming a part of this specification.

Various devices have heretofore been used for the purpose stated, all of which known to me, embody one or more quite serious objections; among them, their cost, their lack of durability, the difficulty of their manipulation and particularly, that the forms which were simple in their construction and method of operation were so made that there was danger in the event of carelessness in manipulating the device, that the cover for the opening would become displaced and drop through the opening into the ashpit or receptacle for the ashes, which is usually located in the cellar, which, of course, necessitated the opening of the ash-pit, the fishing out of the cover and its replacement before a fire could be built upon the hearth or stove. Under my invention I obviate all of these difficulties.

30 Referring to the drawings, Fig. 1 illustrates a plan-view looking down upon the device. Fig. 2 a sectional view thereof on about the line (2) (2) of Fig. 1. Fig. 3 illustrates a front view partly in elevation and partly sectional, of the cover in its elevated position, adapted to be physically removed from the ash drop opening, and Fig. 4 is a view similar to Fig. 3 but at right angles thereto.

In the drawings (1) illustrates a casting, preferably of cast iron and preferably made square and of such dimension that it will lay up well with the brickwork of the hearth. It has an opening (2) through its central portion, which is preferably circular and is also provided with an inwardly extending flange (3) which extends somewhat more than onehalf the entire circumference of the opening, and the surface (4) of this flange is preferably given a downward inclination as shown, so that it may the more readily free itself from ashes. Five (5) is the cover for the opening. It somewhat resembles an ordinary stove lid. It is made

of such size that it will easily fit within 55 the opening (2) in the casting (1) and rest upon the partly completed flange (3), and this cover may be provided, if desired, with a reinforcing rib (6) in order to prevent warping.

60 The operation of the device is as follows: The frame (1) is permanently set in the brick or stone work of the hearth or in the bottom of the stove, as the case may be, as illustrated in Fig. 3. The cover 65 is placed therein, as shown in Fig. 2, in which it rests upon and is supported by the partially incomplete flange (3), the upper surface of the cover and the upper surface of the frame (1) being substantial- 70 ly upon a level. When it is desired to dump the ashes from the hearth or stove bottom, pressure is applied upon the unsupported edge (8) of the cover with a poker or other appropriate means, so that the cover will 75 tilt upon the two ends of the flange (3), they acting as trunnions for the cover. The smaller portion of the cover thereupon descends into the ash chute, whereas its larger portion projects upwardly into the air, as 80 shown in Figs. 3 and 4, and may be readily grasped by the fingers, particularly if a fold of scrap-paper be used, and bodily lifted from the frame (1), thus entirely opening 85 to drop, and it will be particularly noted, because this is an essential feature of my invention, that inasmuch as the flange (3) extends materially beyond the middle line 90 of the opening in the frame (1), as shown in Fig. 1, that, therefore, it is impossible for the cover (5) to drop through the opening in the frame, because the diameter of 95 the cover is such that it will exceed the distance separating any part of the opening in the frame and any part of the flange (3). Thus, it will be physically impossible to lose the cover by reason of its dropping through this opening into the ash-pit below, and it will be further particularly noted that 100 the ashes being dropped through the opening, the cover may be shoved over it again, and that no utensil is needed for the manipulation of the cover and that no care is required as to the adjustment of the cover or 105 as to the side or part that is presented to any other side or part of the apparatus, because it will drop into its place upon being

simply shoved over the opening in the frame, and in so doing will eject the ashes or most of them from the flange (3).

It will be noted that the flange (3) may, if desired, be made sectional, the sections being so located and of such size that it will be impossible to drop the cover through the opening. I prefer, however, to make the flange (3), as shown, since if so it aids in adding solidity to the frame and tends to prevent its warping.

It will be noted that my invention has a series of advantages which I believe have never heretofore been realized. That is to say; extreme simplicity, low cost, great durability, impossibility of dropping the cover into the underlying ash-pit; and entire freedom from care or experience or special utensils necessary for its manipulation.

Having described my invention I claim:

1. An ash drop comprising a frame having an opening therein, a flange partially encircling the opening and a cover for the opening supported solely by said flange, the

relation between the frame and its flange and the cover being such that the latter cannot drop through the opening in the former.

2. An ash drop comprising a frame having an opening therein, an inwardly extending flange extending more than half way around the opening and a cover for the opening adapted to rest therein and be supported by and to tilt upon the ends of the flange.

3. An ash drop comprising an exterior frame having an opening therein, an inwardly extending flange encircling a part only of the opening in the frame and a cover for the opening, the diameter of which is greater than the distance between the unflanged part of the frame and the inner edge of the flange, so that it will be impossible to drop the cover through the opening.

Signed at Yarmouth in the county of Cumberland and State of Maine, this 10th day of July, 1924.

PHILLIPS ABBOTT.

CERTIFICATE OF CORRECTION.

Patent No. 1,525,711.

Granted February 10, 1925, to

PHILLIPS ABBOTT.

It is hereby certified that error appears in the above numbered patent requiring correction as follows:
The present drawing should be canceled and the drawing with the signature of the inventor as shown below
should be inserted therefor as part of the patent:
